UNITED STATES PATENT OFFICE

ALBERT G. DAVIS, OF COLUMBIANA, OHIO, ASSIGNOR TO THE PRODUCTION FOUNDRY CO., OF COLUMBIANA, OHIO, A CORPORATION OF OHIO

BAT

Application filed June 8, 1932. Serial No. 616,138.

The object of the invention is to provide a bat or shelf for use in connection with kiln cars that is of such form as to be of minimum weight with the result that less heat will be absorbed by it; to provide a bat, so constructed that it will not be subject to distortion and will therefore be of longer life in use than the conventional bat; to provide a bat that is so constructed it will act as a baffle plate to check the heat as it rises in the kiln, thereby producing ware more evenly fired; to provide a device of the kind indicated which is constructed in interlocking sections to be interlocked together when placed on the props of a kiln car; and generally to provide a bat which is of simple form and therefore susceptible of cheap manufacture.

With this object in view, the invention consists in a construction and combination of parts of which a preferred embodiment is illustrated in the accompanying drawings but to which embodiment the invention is not to be restricted. Continued use in practice may dictate certain changes or alterations and the right is claimed to make any falling within the scope of the annexed claims.

In the drawings:

Figure 1 is a sectional view on the plane indicated by the line 1—1 of Figure 2.

Figure 2 is a sectional view on the plane indicated by the line 2—2 of Figure 1.

Figure 3 is a top plan view of interlocked bat sections constructed in accordance with the invention.

Figure 4 is a bottom plan view of one of the bat sections illustrated in Figure 3.

Figure 5 is a detail bottom plan view, enlarged, of one of the bat sections.

Figures 6 and 7 are sectional views on the planes indicated by the lines 6—6 and 7—7 respectively of Figure 3.

While the bat constituting the subject matter of the invention may be made of grey iron, semi-steel, cast steel, or any alloy of these, it is essential that it be made in the

grid form shown, so as to provide transverse and longitudinal series of openings 10, separated by intervening web portions 11. Each section of the bat is formed with a marginal pendent flange 12 extending throughout its periphery and with intervening ribs 14 disposed on the under faces of the webs and at the bounding edges of the openings 10.

The webs are formed with openings 15 arranged in continuous series and these openings or perforations 15 have their bounding edges beveled downwardly as indicated at 16, being of the shape as if they were countersunk from the under faces of the webs.

The bat sections are formed at their corners, as indicated at 17, with openings, and are similarly formed at the middle, with such openings as indicated at 18. These openings are preferably square, so that they may receive the lower squared ends of the spacers 19 through which the tie bars 20 pass in assembling the bat sections on the props 21 of the kiln car 22.

The bats, it will be observed, are arranged in superposed relation on the props 21 and the tie bars 20 have their heads 23 seated in the recessed portions around the holes 17, so that the bat or shelf is free from obstruction on the top. The spacers 19 of course occupy some space on the upper surface of the intermediate bats, but this cannot be avoided since they are necessary to equally space the superposed series of bats.

In those kilns in which the ware is fired on the revolving platform or base, the bats constituting the present invention will be mounted in the customary manner on such platform and, where it is customary to loosely mount the bats on the props relying on the sides of the kiln to keep them in place, the present invention is also applicable, being mounted on the props according to the conventional practice.

But where anchored on the car, as by the tie rods 20, the present construction pro-

vides, if desired, for interlocking adjacent sections and to this end one section is provided with a disk-like extension 24 connected with the body portion of the bat by a neck 5 section 25, both these being bounded with a flange 26 of the height of the flanges 12 and the ribs 14. The disk extension is disposed adjacent one edge of the bat, while adjacent the other edge, there is formed in the bat a 10 circular opening 27 having a clearance slot 28 opening onto the edge of the section. In connecting adjacent bats together, the tongue extension 24 of the one seats in the opening 27 of the other, the neck 25 being received in the slot 28.

This interlocking connection is clearly disclosed in the two connected bat sections illustrated in Figure 3.

By reason of the bat being formed in the 20 grid shape shown with the crossing ribs 14 and marginal flanges 12, the bat is reinforced against distortion due to the high heat to which it will be subjected in practice. But the openings 10, as well as the openings or 25 perforations 15, prevent the heat rising through the bat to contact with the ware carried thereon on all sides, so that the ware thus becomes effectively fired.

The invention having been described, what 30 is claimed as new and useful is:

1. A kiln car bat comprising a grid-like body having a marginal pendent flange and transverse and longitudinal ribs on the under side.

35 2. A kiln car bat comprising a grid-like body having its openings arranged in transverse and longitudinal series and the web portions separating the openings provided on their under faces with pendent ribs extending all around the edges of the openings.

40 3. A kiln car bat comprising a grid-like body having its openings arranged in transverse and longitudinal series and the web portions separating the openings provided on their under faces with pendent ribs extending all around the edges of the openings, the body being bounded with a continuous pendent flange of the depth of the ribs.

45 4. A kiln car bat comprising a grid-like body having its openings arranged in transverse and longitudinal series and the web portions separating the openings provided on their under faces with pendent ribs extending all around the edges of the openings, the web portions being formed with perforations.

50 5. A kiln car bat comprising a grid-like body having its openings arranged in transverse and longitudinal series and the web portions separating the openings provided on their under faces with pendent ribs extending all around the edges of the openings, the web portions being formed with perforations countersunk from the bottom faces of the web portions.

55 6. A kiln car bat comprising a grid formed

at one edge and adjacent one side with an extending tongue comprising a body portion and a neck portion connecting the body portion with the grid, the body portion being materially wider than the neck portion, the 70 grid being formed adjacent the opposite side with an opening dimensioned according to the neck and body portion of the tongue for the reception of the tongue of an adjacent grid when the tongue of the first grid enters 75 the opening in the adjacent grid.

In testimony whereof I affix my signature.

ALBERT G. DAVIS.
